UNITED STATES PATENT OFFICE.

WILLIAM M. SCOTT, OF PHILADELPHIA, PENNSYLVANIA, ASSIGNOR TO THE CUTTER ELECTRICAL AND MANUFACTURING COMPANY, A CORPORATION OF NEW JERSEY.

AUTOMATIC MAGNETIC CIRCUIT-BREAKER.

940,647.

Specification of Letters Patent. Patented Nov. 16, 1909.

Application filed January 19, 1907. Serial No. 353,047.

To all whom it may concern:

Be it known that I, WILLIAM M. SCOTT, a citizen of the United States, residing at Philadelphia, in the county of Philadelphia and State of Pennsylvania, have invented a new and useful Automatic Magnetic Circuit-Breaker, of which the following is a specification.

My invention relates to electrical switches 10 and more particularly to automatic switches or circuit breakers, and particularly electrical switches or circuit breakers suitable for handling very heavy currents, as, for example, hundreds or thousands of amperes. 15 My invention resides in efficient means for operating or controlling a movable switch contact suitable for carrying very heavy currents, such means comprising force-multiplying mechanism which enables 20 an operator to effectually and easily close the switch by a moderate sweep of the operating handle. By my invention, the operating handle protrudes from the base or switchboard a small distance only when considering the size of switch contact to be operated.

My invention resides also in other features hereinafter described and pointed out in the claims.

30 For an illustration of a form my invention may take reference is to be had to the accompanying drawing, in which:

Figure 1 is a side elevation of an automatic circuit breaker embodying my invention. Fig. 1^a is a fragmentary view of the side elevation shown in Fig. 1, parts being broken away for the sake of clearness. Fig. 2 is a side elevation of the cam member. Fig. 3 is a front elevation of the same. Fig. 4 is a side elevation of the tripping member. Fig. 5 is a front elevation of the same. Fig. 6 is a side elevation of the latch. Fig. 7 is a front elevation of the same.

45 Referring to Fig. 1, 1 and 2 represent terminal blocks of copper secured upon the front of the base or switchboard 3, of insulating material, by the nuts 4 and 5 respectively engaging upon screw threaded 50 studs communicating with said terminal blocks. The movable contact member 6 is of the laminated type secured upon but insulated from the arm 7, pivoted at 8 to the bracket 9 secured upon the base. Secured 55 upon the upper main contact 1 is a metallic

shunt contact piece 10 with which co-operates the movable metallic shunt contact piece 11 supported by the spring 12 upon the arm 7. Also secured upon and in electrical communication with the terminal block 1 is 60 the bracket 13 to which the stationary carbon contact 14 is provided at 15. The movable shunt carbon 16 co-operates with the carbon 14 and is supported upon a spring 17 carried by the arm 7. 65

Pivoted in the arm 7, at 18, is the roller 19, which is adapted to engage the cam surface 20 of the cam member 21, pivoted in the bracket 9 at 22. The cam surface 20, at the region where it is engaged by the roller 19 70 when the parts are in open circuit position, has a relatively great pitch so that the parts move quickly for a given angular movement toward circuit closing position. When the laminated member 6 engages the main contact blocks the cam surface 20 changes quite abruptly into a part having very slight pitch, whereby with considerable remaining angular movement of the member 21, slight travel of the laminated member 6 is effected, 75 but with very considerably increased force. The cam member 21 extends downwardly 80 beyond the pivot 22 in the separated wings 23 and 24. In each of the wings 23 and 24, is disposed a cam slot 25. The shape of the 85 slot and its arrangement with respect to the cam member 21, is such also as to have in effect a cam surface of slight pitch especially near the end of the circuit closing movement, thus exerting a powerful force upon the cam 90 member 21 during the period of cramping the laminated member 6 against the main contact terminals 1 and 2. In each of the cam slots 25 is a roller 26 mounted upon pin 95 27, the pin 27 being secured at its ends in the ears 28, secured to and extending downwardly from the lever 29, pivoted to the bracket 9 at 8. Pivoted at 8 also is the operator's lever 30, having the handle 30', and having the upward extension 31 to which is 100 secured one end of the helical spring 32 whose other end is secured to the lever 29, the spring 32 being under tension, as shown in Fig. 1, when the parts are in circuit closing position, and whenever the levers 29 and 105 30 are latched together. Secured to the operator's lever 30 is a member 33 to which is pivoted, at 34, the latch 35, which is bifurcated, as shown in Fig. 7, and carries at its outer end an anti-friction roller 36. The 110

hook of the latch 35 is adapted to engage and hold the roller 37, mounted upon the pin 27 and disposed between the wings 23 and 24 of the cam member 21.

5 A tripping member 38 is pivoted in the bracket 9 at 22 independently of the cam member 21. This tripping member has a downward extension 39, whose surface 40 is adapted to engage the roller 36 on the latch 35 to actuate said latch. It also has a shorter extension 41, which lies in the path of travel of the lever 42, pivoted to the frame at 43 and having the extensions 44 and 45. The extension 44 is adapted to be 10 engaged by the projection 46 upon the armature 47, pivoted at 48 and adapted to normally rest upon the non-magnetic stop 49 between the cores 50 and 51 of two coils 52 and 53 respectively. The third coil 54 has 15 for its core the pivotally mounted cross connecting member between the two similar armatures 47. And the extension 45, of the lever 42, lies in the path of the pivoted armature 55 of the overload tripping magnet which is pivoted on an axis normal to the 20 front face of the switchboard 3.

The cam surface 20 of the cam member 21 is of such shape that with the parts in open circuit position, the subsequent clockwise rotation of the cam member 21 about its pivot 22, forces the roller 19 and, therefore, the arm 7 very rapidly toward circuit closing position during the initial movement. When the laminated bridging member 6 has come 30 into engagement with the terminal blocks 1 and 2, the first real mechanical resistance is offered and from that time on to full circuit closing position, the greatest amount of force must be exerted. During such closing period, the part of the cam surface 20 which is engaged by the roller 19, increases in distance from the pivot 22 by relatively slighter increments than in the earlier part of the movement. This permits, as stated, 35 a free and rapid closing of the movable contact member 6 during the first part of the closing movement, and for the remainder of the closing movement the movement of the member 6 is very slight, the cam member 21 exerting, however, greatly increased force to 40 cramp the laminated contact member 6 into full circuit closing position. The rollers 26, carried by the lever 29, engage in the cam slots 25 of the two wings 23 and 24 of the cam member 21. The cam slot 25 is of such 45 shape also that, near the end of the closing movement very great force is exerted to rotate the cam member 21 in a clockwise direction, the lever 29 moving a considerably 50 greater distance than the cam member 21.

With the parts in the open circuit position, the operator raises the lever 30, until the latch 35 engages the roller 37, carried by the lever 29, which lever in the open circuit 55 position, is elevated above the position

shown in Fig. 1, with the rollers 26 at or approximate the upper ends of the cam slots 25. With the handle 30 thus locked to the lever 29, the operator depresses the lever 30 causing relatively great angular movement 70 in a clockwise direction of the cam member 21 about the pivot 22 until near the end of the circuit closing movement when the cam member 21 moves more slowly and exerts greater force. When the position shown in 75 Fig. 1 has been reached the switch is locked in circuit closing position because the strain exerted by the cam member 21 against the pin 27, which is locked by latch 35 to lever 30, is in such direction that the parts cannot move to open position.

Assuming the circuit breaker closed, as shown, either when by overload the armature 55 is actuated, or the armature 47 is actuated, the lever 42 is rotated in a clockwise direction about its pivot 43 striking the extension 41 of the tripping member 38 whose longer extension 39 then engages by its surface 40 against the roller 36 carried by the latch 35, tilting that latch in a clockwise direction about its pivot 34 to release the roller 37. In other words, upon the actuation of either of the electro-responsive means, the latch 35 is actuated and the lever 29 released from the lever 30. Then, due to 95 the tension of the spring 32, as well as to the spring effect exerted by the laminated member 6, and gravity, the lever 29 rises about its pivot 8 and the cam member 21, being thus released from the locking lever 100 29, rotates in a counter-clockwise direction, so that first the laminated bridging member separates from the main contacts 1 and 2, later the metallic shunt contact piece 11 separates from the shunt contact piece 10, 105 and finally, the carbon 16 separates from the carbon 14. If, upon attempting to close the circuit breaker, an abnormal circuit condition exists, either an abnormal condition of 110 overload or potential variation, after having raised the handle 30 to lock it to the lever 29 and depressing the same in closing movement, as soon as first substantial contact is made, either one or the other of the electro-responsive means will operate to tilt 115 the latch 35, to unlock member 21 from the lever 29. So it is that the operator is robbed of control if there exists an abnormal circuit condition, and the parts cannot be moved to or locked in the full circuit closing position.

What I claim is:

1. In an electrical switch, the combination with a fixed terminal block, of a movable laminated contact member, a cam member 125 for cramping said laminated contact member against said terminal block, a second cam member for actuating said cam member, the pitches of the portions of the surfaces of said cam members, active during said 130

cramping movement, being slight, said cam members serving to restrain said laminated contact member in normal position.

2. In an electrical switch for heavy currents, the combination with a fixed terminal block, of a movable laminated contact member, a cam member for cramping said laminated contact member against said terminal block, the pitch of the surface of said cam member, active during cramping movement, being slight, a second cam member for actuating said cam member, said cam members serving to restrain said laminated contact member in normal position, the locking strain being transmitted through said cam members.

3. In an electrical switch, the combination with a movable contact member, of a cam member for actuating the same, a member engaging said cam member to actuate the same by cam action, an actuator, and means for locking said actuator to said member.

4. In an electrical switch, the combination with a movable contact member, of a cam member for actuating the same, a member for actuating said cam member by pin and slot engagement, an actuator, and a latch for locking said actuator to said member, whereby said cam member may be actuated to move said contact member to normal position, said member when latched to said actuator constituting means for restraining said contact member in normal position.

5. In an electrical switch, the combination with a movable contact member, of a cam member for actuating the same, a lever engaging with said cam member to actuate the same by cam action, an actuator lever, and means for locking said levers together, whereby said actuator lever may move said contact member to normal position.

6. In an electrical switch, the combination with a movable contact member, of an independent cam member for actuating the same, a cam slot in said cam member, a lever engaging in said cam slot to actuate said cam member, an actuator lever, and a latch for locking said actuator lever to said lever, whereby said levers operate as a unit to actuate said cam member and serve as means for restraining said contact member in normal position.

7. In an electrical switch, the combination with a movable contact member, of a cam member for actuating the same, and levers concentrically pivoted and latched together for actuating said cam member and restraining said movable contact member in normal position.

8. An automatic circuit breaker comprising a movable contact member, a cam member for actuating said contact member, a member engaging said cam member to actuate the same by cam action, an actuator, a latch for connecting said actuator and said

member, and electro-responsive means for actuating said latch upon movement of said contact member to normal position during the existence or continuance of predetermined electrical conditions.

70

9. An automatic circuit breaker comprising a movable contact member, a cam member for actuating the same, a lever engaging said cam member to actuate the same by cam action, an actuator lever, a latch connecting said levers, whereby said contact member is locked in normal position, and electro-responsive means for actuating said latch.

75

10. In an electrical switch, the combination with a movable contact member, of means for actuating the same comprising pivoted levers latched together, one of said levers serving as a lock for said movable contact member, and a spring acting between said levers.

80

11. In an electrical switch, the combination with a movable contact member, of means for actuating said contact member comprising concentrically pivoted levers latched together, a spring acting between said levers, and a cam intervening between said latched levers and said contact member.

85

12. In an electrical switch, the combination with a movable contact member, of a pivoted lever for operating the same and serving as a lock, an actuator, a latch connecting said actuator and lever, and a spring acting between said lever and said actuator.

90

13. In an electrical switch, the combination with a movable contact member, of a cam member engaging the same, a pivoted lever for operating said cam member, an actuator, a latch connecting said pivoted lever and actuator, and a spring acting between said lever and said actuator.

100

14. In an electrical switch, the combination with a movable contact member, of a cam member engaging the same, a pivoted lever for operating said cam member, an actuator pivoted concentrically with said lever, and a latch connecting said lever and actuator.

105

15. In an electrical switch, the combination with a movable contact member, of a cam member engaging the same, a pivoted lever engaging said cam member, an actuator, a latch connecting said lever and actuator, and a spring joining said lever and actuator.

115

16. In an electrical switch, the combination with a movable contact member, of cam members for operating the same, a pivoted lever for operating said cam members, an actuator pivoted concentrically with said lever, a latch connecting said lever and actuator, and a spring joining said lever and actuator.

120

17. In an electrical switch, the combination with a movable contact member, of a pivoted lever for actuating said contact

125

130

member, an actuator pivoted concentrically with said lever, a latch connecting said lever and actuator, and a spring connecting said lever and actuator and disposed to separate 5 said lever and actuator when unlatched.

18. In an electrical switch, the combination with a movable contact member, of a cam member for actuating the same, a pivoted lever for engaging said cam member, 10 an actuator, and a latch connecting said actuator and lever.

19. In an electrical switch, the combination with a movable contact member, of a cam member for actuating the same, a pivoted lever for engaging said cam member, 15 an actuator, a latch connecting said actuator and lever, and a spring joining said lever and actuator.

20. In an electrical switch, the combination with a movable contact member, of means for actuating the same comprising a pivoted lever, a pivoted actuator, and a latch pivoted to said actuator and locking the same to said lever, said lever serving as a 25 lock for restraining said contact member in normal position.

21. In an electrical switch, the combination with a movable contact member, of a cam member for actuating the same, and 30 pivoted levers latched together for actuating said cam member, one of said levers serving as a lock for said cam member for restraining said contact member in normal position.

35. 22. In an automatic circuit breaker of the "non-closable" type, the combination with a movable contact member, of a member for operating the same, a pivoted lever engaging said operating member and serving to 40 lock the same, a pivoted actuator, a latch locking said lever and actuator together, and electro-responsive means for actuating said latch to disconnect said lever from said actuator.

45. 23. In an automatic circuit breaker of the "non-closable" type, the combination with a movable contact member, of means for actuating the same comprising a pivoted lever, a pivoted actuator, a latch locking said lever and actuator together, said lever serving as 50 the lock for restraining said contact member in normal position, and electro-responsive means for actuating said latch.

55. 24. In an automatic circuit breaker of the "non-closable" type, the combination with a movable contact member, of a cam member for operating the same, a lever for operating said cam member and serving as a lock for the same, an actuator, a latch connecting 60 said lever and actuator, and electro-responsive means for actuating said latch.

25. In an automatic circuit breaker of the "non-closable" type, the combination with a movable contact member, of a cam member for actuating the same, a single latch, a 65

pivoted lever engaging said cam member, a pivoted actuator, said lever and actuator connected by said latch, and electro-responsive means for actuating said latch.

26. In an electrical switch, the combination with a movable contact member, of a cam member for actuating the same, a lever for actuating said cam member by cam action and serving as a lock for said cam member, an actuator, a latch for connecting 75 said actuator and lever, and a spring acting between said lever and actuator.

27. In an electrical switch, the combination with a movable contact member, of a pivoted operating member therefor, a lever 80 for actuating said operating member, an actuator, a latch connecting said lever and actuator, and a latch actuating member pivoted concentrically with said operating member.

85. 28. In an electrical switch, the combination with a movable contact member, of a cam member for operating the same, a lever for actuating said cam member, an actuator, a latch connecting said lever and actuator, 90 and a latch actuating member pivoted concentrically with said cam member.

29. In an electrical switch, the combination with a movable contact member, of a cam member for operating the same, a lever 95 for operating said cam member by cam action and for locking said cam member, an actuator, and a latch connecting said lever and actuator.

30. In an electrical switch, the combination with a movable contact member, of a cam member for operating the same, a lever for operating said cam member and serving as a lock for the same, an actuator, a spring and a latch connecting said lever and actuator, 100 and means for actuating said latch to release said lever to the influence of said spring, whereby said cam member is unlocked.

105. 31. In an electrical switch, a hook latch, 110 a latch actuating member, and a roller pivoted in said hook latch and adapted to be engaged by said latch actuating member.

32. In an electrical switch, the combination with a movable contact member, of means for operating the same having a slot, 115 a lever, a member carried by said lever and engaging in said slot and serving to lock said operating means, a spring engaging said lever, a latch engaging said lever, and 120 means for actuating said latch to release said lever to the influence of said spring, whereby said operating means are unlocked.

125. In testimony whereof I have hereunto affixed my signature in the presence of the two subscribing witnesses.

WILLIAM M. SCOTT.
